UNITED STATES PATENT OFFICE

FRANK C. FERGUSON, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA

METALLIC FURNITURE

Application filed March 29, 1932. Serial No. 601,736.

This invention relates to metallic furniture, and particularly to articles of furniture having legs or posts, such as tables, cabinets, and the like. The invention is especially concerned with the attachment of legs or posts to the main structure or body of the article to which they belong. It is one aim of the invention to provide a simple, strong, rugged, construction of this character, that can be easily and inexpensively manufactured, and quickly and easily assembled and set up. In suitable forms of embodiment, such as hereinafter described, the invention allows articles of furniture to be compactly packed for shipment, with their legs detached, and to be easily and quickly set up by the ultimate user, or by any unskilled person.

In the drawing, Fig. I is a fragmentary side view of a table embodying the invention in one simple and advantageous form of construction, a portion of the table top and one leg being broken away to expose the attachment of the leg behind.

Fig. II is a tilted or perspective inside view of the corner portion of the box frame of the table.

Fig. III is a tilted or perspective view of the upper end of a table leg.

The table here shown has a box frame 5 of sheet metal of channel section, and a flat top 6 of any suitable thin but strong sheet material secured thereto. As shown in Fig. I, cross braces 7 of sheet metal, stiffened with semi-circularly embossed ribs 8, extend across the frame 5 and afford intermediate support for the table top 6. The ends of these cross braces 7 are secured (welded) to the lower side of the upper flange of the channel frame

5, these ends being offset downward as indicated at 9 to accommodate the frame flanges. The table legs 10 are of sheet metal bent or rolled to a generally angle section, such as shown in Fig. III. As here shown,

45 the angle leg 10 is reinforced with an extra flange 11 projecting inward from about the mid-line of one of its main flanges 12, and formed by folding the sheet metal of the flange 12 back on itself at 13 and then bending it inward at right angles at 14. The

other main flange 12 has its edge strengthened by doubling the margin inward as shown at 15. The legs 10 are mounted and secured inside the box frame 5 at its corners, the lower flange of the frame 5 being cut away at the corners for this purpose, as most clearly shown in Fig. II. For securing the legs 10 in the corners of the frame 5, they are interlocked by socket means on one of the parts and corresponding heads on the other. As shown in Figs. II and III, the socket means are on the frame 5, and consist of outward-offset downward-converging pairs of ears 20 on an angle plate 21 mounted and secured (welded) in the corner of the frame 5. These ears 20 are formed by shearing and punching out the sheet metal of the plate 21. The heads are on the legs 10, and consist of outward-offset downward-converging pairs of ears 22 on an angle plate 23 mounted and secured (welded) on the upper end of the leg 10, these ears 22 being formed by shearing and punching out the sheet metal of the plate 23. The leg-ears 22 are adapted to hook behind the table ears 20, and the head formed by each converging pair of leg-ears 22, 22 is adapted to wedge securely between the socket formed by the corresponding pair of table ears 20, 20.

As shown in Fig. II, the angle plate 21 has depending tabs or lugs 24, 24, projecting downward below the lower flange of the box frame 5. The ends of the angle plate 23 project or extend to either side beyond the vertical edges of the leg 10. When the leg 10 has been properly affixed to the table top by forcing its heads 22 up into the sockets 20 as far as they will go, so as to interlock and wedge them securely and firmly, the ears 24 are bent inward and upward around and against the lower edge of the leg-angle 23, so as to secure the leg to the frame and prevent disengagement of its heads or ears 22 from the box frame socket ears 20. This can be done very easily, either by a few blows of a hammer, or by means of suitable pliers or the like.

Owing to the wedging of the heads 22, 22 of a leg 10 in the table-frame sockets 20, 20 in the planes of the adjacent table sides,

which lie at right angles, a very rigid attachment of the legs to the table is produced. This attachment is securely maintained against disengagement or loosening by the 5 forcible interlocking of the bent-up lugs 24.

Having thus described my invention, I claim:

1. A leg attachment construction for metallic furniture comprising a sheet metal box-
10 frame having on adjacent sides at its corner pairs of upward-converging inward-offset ears, a post or leg structure having on adjacent sides undercut heads for hooking behind said ears and wedging between them,
15 and means for securing said leg structure against disengagement of its heads from said ears.

2. A leg attachment construction for metallic furniture comprising a sheet metal box-
20 frame having secured in its corner an angle-plate with pairs of upward-converging inward-offset punched-out ears, and downward projecting tabs, and a post or leg having corresponding pairs of outward-offset ears and
25 lateral projections, said post ears being hooked behind said angle-plate ears, and said angle plate tabs being bent up under said lateral projections of said post structure, so as to prevent disengagement of the post ears from
30 the angle-plate ears.

In testimony whereof, I have hereunto signed my name at Philadelphia, Pennsylvania, this 3rd day of March, 1932.

FRANK C. FERGUSON.
